US00D988286S

(12) **United States Design Patent** (10) Patent No.: **US D988,286 S**
(45) Date of Patent: **** Jun. 6, 2023**

(54) **WIRELESS SPEAKER**

(71) Applicant: **Jieqing Xiong**, Shenzhen (CN)
(72) Inventor: **Jieqing Xiong**, Shenzhen (CN)
(**) Term: **15 Years**
(21) Appl. No.: **29/761,016**
(22) Filed: **Dec. 7, 2020**
(51) LOC (14) Cl. **14-01**
(52) U.S. Cl. .... **USPC D14/216**
(58) **Field of Classification Search**

USPC D14/314, 341, 356, 362, 363, 365, 366, D14/368, 369, 388, 432, 498-507, 509, D14/510, 129, 131, 159, 168, 169, 171, D14/172, 175, 188, 194, 199, 202, 203, D14/203.1, 203.3, 203.4, 203.6, 203.7, D14/204, 209.1-216, 217, 221, 218, 261, D14/211, 208, 200, 187, 224, 173, 207
